UNITED STATES PATENT OFFICE.

MARCEL H. POIRIER, OF WOONSOCKET, RHODE ISLAND.

COUPLING.

1,340,739.

Specification of Letters Patent. Patented May 18, 1920.

Application filed December 22, 1917. Serial No. 208,467.

To all whom it may concern:

Be it known that I, MARCEL H. POIRIER, a citizen of the United States, residing at Woonsocket, in the county of Providence and State of Rhode Island, have invented 5 certain new and useful Improvements in Couplings; and I do hereby declare the following to be a full, clear, and exact description of the invention, such as will enable 10 others skilled in the art to which it appertains to make and use the same.

This invention relates to new and useful improvements in train line couplings, and the principal object of the invention is to 15 provide a device for use in coupling the train-lines of railway cars and the like.

Another object of the invention is to provide a coupler which is adapted to be used whether the cars are standing on a curve or 20 on straight rails.

A further object of the invention is to provide a device in which the coupling knuckles will be automatically guided to the proper positions and will be firmly locked 25 after the coupling process is completed.

Still another object of the invention is to provide a device which will allow for the free movement of the draw bars when the cars are rounding a curve so as to avoid any 30 possibility of pulling the couplers apart.

With these and other objects in view, the invention consists in the novel combination and arrangement of parts as will be fully set forth in the following specification and 35 accompanying drawings, in which:—

Figure 1 is a bottom plan view of a car equipped with this improved coupler;

Fig. 2 is a vertical sectional view through Fig. 1;

Fig. 3 is an enlarged detail end view of 40 one of the couplers;

Fig. 4 is a side elevation of Fig. 3;

Fig. 5 is a top plan view of a pair of 45 couplers showing the same as they would appear prior to being coupled;

Fig. 6 is a similar view showing the couplers after they have been coupled;

Fig. 7 is a detail perspective view of one 50 of the coupling knuckles;

Fig. 8 is a detail perspective view of one 55 of the latches for holding the knuckles in coupled position.

Fig. 9 is a detail view of one of the collars for engaging the train pipes in the pipe 60 chest.

Fig. 10 is a detail view of one of the coupling rings for holding the flexible pipes in connection with the rigid pipes,

Fig. 11 is a detail sectional view through 60 one of the pipe couplings, and

Fig. 12 is an end elevation of a modified form of coupler showing the same adapted for use on freight cars.

Referring to the drawings, the numeral 1 designates a car of the ordinary construction provided with the usual axle 2 and wheels 3. The train pipes are designated by the numeral 4 and extend in spaced parallel relation longitudinally of the car as will be clearly seen upon reference to Fig. 1. 70 Suitable depending angle brackets 5 extending in parallel relation are attached to the under side of the car body and slidably between said brackets is the draw bar 8. The draw bar 8 is supported by a strap 8^a and 75 the draw bar is free to swing laterally. Bars 7 are attached to the draw bar 8 and project laterally therefrom and are received in a slot in the angle brackets 5. Springs 9 surround the bars 7 and bear against the 80 washer 10^a on the outer surface of the angle brackets 5 and against the washer 10 carried by the ends of the bars 7 and form yieldable centering means by which the coupler head is maintained in place. Suitable nuts 10^a hold the washer 10 in place. 85

Connected to the end of the draw bar 8 by suitable bolts 6 is the yoke 11 and a compression coil spring 10^b is seated therein and the coil spring bears against plates 11^a slidably mounted in the yoke, and these plates 90 bear against lugs (not shown) carried by the brackets 5 and yieldably hold the coupler in such position as to be engaged by the coupler of the adjacent bar. Each draw 95 bar 8 is provided at its forward end with a coupler head designated generally by the numeral 11^b which comprises a body 12 formed with a solid head portion 13, which has projected from its forward face, at the lower portion thereof, a dowel pin 14 and formed in spaced relation thereto is a socket or recess 15. As illustrated in Fig. 3, it

will be seen that the pins and recesses are in such a position that the pins and recesses of the adjacent cars will interlock in the manner illustrated in Figs. 5 and 6. The sockets 15 have their outer surfaces inclined inwardly as at 15^a so as to facilitate the entrance of the dowel pins 14 thereinto 110

and the dowel pins 14 are provided with inclined enlargements 14^b adjacent the body 13. The body 12 is formed with a pocket 16 which is adapted to accommodate the coupling knuckles which will be more fully hereinafter described. As illustrated in Fig. 4 it will be seen that the pocket extends from the top of the head 13 to a point near the lower end of the body and adjacent to the dowel pins 14 and formed at the forward edge of the lower walls of the pocket are the inclined faces 17 which act as guides when the couplers are moved toward each other in order to insure the proper positioning of the couplers with relation to each other.

Attached to the under side of the body 13 is the pipe chest designated by the numeral 18 which comprises a hollow body 19 provided with an open side wall, which is closed by a hinge cover 20, the pintle 21 of which is surrounded by a coiled spring 22, one end of which engages a cover while the opposite end of the spring engages the side edges of the lower end of the head. A handle 22^a is provided for the cover 20 whereby the same can be easily operated, so that access may be readily had to the pipes for repairs and the like. Formed in the front and rear walls of the body 19 of the pipe chest are aligned apertures 23 through which the rigid pipes 24 are slidable. These pipes are connected by hose or the like 25 to rigid V-shaped branch pipes 26 which are connected to the train pipes 4. Suitable rings 27 connect the flexible pipes 25 to the rigid pipes and these rings as shown in Fig. 10 are split and have their ends bent angularly as at 28 to receive the adjusting screw and nut 29. Collars 30 are carried by the pipes 24 within the pipe chest for engagement against one end of the compression coiled springs 31, the other end of which engages the rear wall of the pipe chest 18, so as to normally tend to move the forward ends of the pipes 24 outwardly. The collars 30 are split and are provided with notched portions 32 adjacent the free ends thereof and the ends are apertured to receive an adjusting nut and screw 33 by means of which the collars are held in position on the pipes 24. Each of the pipes 24 has threaded thereon a socket 34 provided with a flange 35 which is recessed as at 36 in its forward face to receive a gasket 37 of a relatively soft material such as rubber or the like. The gasket 37 extends beyond the recess in the flange 35 and the walls of the recess are bent inwardly as at 38 into engagement with the sides of the gasket 37.

Formed on the upper and lower walls of the body 11^b are extending ears 39 which are apertured to receive the pivot bolts 40 of the knuckles designated generically by the numeral 41. These knuckles are illus-

trated in detail in Fig. 7 and each of them comprises a cylindrical body 42 having extending therefrom a relatively small arm 43 while a coupling arm 44 extends from the body at an angle of substantially thirty degrees with relation to the arm 43. The arm 43 has a rounded back 43^a, so as to throw the latch, which will be hereinafter described, when the same is in operative position. Recesses 17^a and 17^b are formed adjacent the pocket 16 for receiving the pivot bolts 40 of the couplers, when the same are in locked position. Recesses 45 are formed in the upper and lower ends of the body and are adapted to accommodate the ears 39, 80 while an axial aperture 46 extends longitudinally through the body 42 and receives the pivot bolts 40 hereinbefore described. Upon reference to Figs. 5 and 6 it will be seen that as the two knuckles come together they will move into folded position illustrated in Fig. 6 thereby locking the parts against relative movement.

In order to lock the knuckles in place after the coupling has been effected, a sliding latch member 47 is slidable in the pocket 16 and is provided with an inclined guide 48, which rides in an inclined guide way 49 so that upon upward movement of the latch the same will move rearwardly and away from contact with the knuckle. Secured to the latch and extending upwardly therefrom through a suitable opening 50 is a pull wire 51. The coupling knuckles are arranged to swing directly into the coupler body and into engagement with the latch 47, so as to loosen the latch and thus permit the couplers to be separated when so desired.

In operation, the pull wire 51 is pulled upwardly, which will raise the latch 47 and carry its guide 48 forwardly out of the guide way 49 and the knuckles in opening will engage the knob 47^b formed on the latch 47, in passing and push the latch on its base. In closing, the knuckles will hit the inclined rib 47^a formed on the latch 47 and will raise the latch until the knob 47^b is positioned on top of the knuckles. The rounded portion 43^a of the small arm 43 of the knuckles engages the inclined portion 48^a of the latch 47 and pushes its guide 48 into place in the guide way 49. When the latch is down and the knuckle is opened the rounded portion 43^a of the knuckle engages the slanting rib 47^a of the latch and raises the guide 48 out of the guide way 49 and permits the knob 47^b to pass over the small arm 43 when the knuckle has reached its innermost position. The latch then drops back into the guide way 49 and the couplers are then securely held in engagement with each other. The guide ways 49 have a communicating opening, which extends entirely through the block 13 and allows cin-

ders and dirt and the like to pass out of the guide way 49.

It will be apparent from the foregoing, that in use, when the couplers move toward each other the knuckles will swing on their pivots into the position illustrated in Fig. 6 and the pins 14 will enter the openings 15, thereby firmly locking the whole in place. The movement of the coupler will cause the ends of the pipes 24 to abut so that the gaskets 37 form air tight joints which will prevent the escape of fluid from the train pipes and yet allow the train pipes to be readily coupled and uncoupled.

In order to prevent the escape of fluid from the train pipes when the couplers are disconnected, suitable valves 52 are arranged in the V-shaped branch pipes 26 and provided with valve rods 53 extending through the side of the car and through angle plates 54 attached to the under side of the car and it will thus be seen that the movements of the valves may be readily controlled from either side of the car. In addition to the couplers above described, the end of each train pipe is provided with a valve 55 having connected thereto a flexible hose 56 provided with a coupler head 57 which may be used in case of emergency when the main coupler is not in use and in such places as where one car is provided with the ordinary type of coupler and the next adjacent car with the improved coupler hereinbefore described.

In Fig. 12 is illustrated a modified form of the coupler, which is especially adapted for freight cars and is identical in con-

struction with the other couplers with the exception that the pipe chest 18 is provided with only one pipe 24, as is usual in freight 40 car construction.

While in the foregoing there has been shown and described the preferred embodiment of this invention, it is to be understood that such changes may be made in the combination and arrangement of parts as will fall within the spirit and scope of the amended claim.

What is claimed is:—

The combination with the air and steam pipes of a railway car, flexible hose secured to the ends of said pipes and carrying couplings, and a coupling head carried by each end of the car and mounted for yielding movements longitudinally and laterally, 55 with relation to the car, of valved branch pipes communicating with said air and steam pipes inwardly of their ends, a chest carried by each coupler head, pipes slidably mounted in said chest and extending 60 beyond the inner and outer walls thereof and provided at their outer ends with couplings, springs located in the chests and urging the slidable pipes outwardly, and flexible pipes communicating with said 65 branch pipes and with the pipes carried by said chests.

In testimony whereof I affix my signature in presence of two witnesses.

MARCEL H. POIRIER.
